J. M. GRAY

END GATE

Filed Mar. 20, 1922

UNITED STATES PATENT OFFICE.

JOSEPH M. GRAY, OF BROWNSTOWN, INDIANA, ASSIGNOR OF ONE-THIRD TO JOSEPH M. ROBERTSON AND ONE-THIRD TO MARTIN P. PFERRER, BOTH OF BROWNSTOWN, INDIANA.

END GATE.

Application filed March 20, 1922. Serial No. 545,263.

To all whom it may concern:

Be it known that I, JOSEPH M. GRAY, a citizen of the United States, residing in Brownstown, in the county of Jackson, 5 State of Indiana, have invented new and useful Improvements in End Gates, of which the following is a full, clear, and comprehensive specification and exposition, the same being such as will enable others to 10 make and use the same with exactitude.

The object of my present invention, broadly speaking, is to provide an end-gate for vehicles, and for various other purposes to which it may be found applicable, the same 15 being strong and durable in construction, easily operated and controlled, efficient in practice, and which can be manufactured and sold at a comparatively low price.

Various other objects and particular advantages of the invention will suggest themselves in the course of the following specification, and that which is new will be correlated in the appended claim.

Certain details of this construction are 20 shown in my application for patent on end gate latches, filed March 20, 1922, Serial No. 545,264, now pending in the Patent Office.

The preferred manner of carrying out 25 the principles of this invention in an efficient manner is shown in the accompanying drawings, in which—Figure 1 is a face view of my invention in practice, or more particularly, a rear end elevation of a vehicle bed 30 with my end gate secured in operative condition therewith. Figure 2 is a top plan view of one portion of the construction shown in Fig. 1. Figure 3 is a side elevation of the same. Figure 4 is a detail section, as taken on the line 4—4 of Fig. 3. 35 And Figure 5 is a detail top plan or edge view of the rear end of one of the sides of the vehicle body.

Similar indices denote like parts throughout the several views.

In order that the construction, the operation, and the advantages of the invention may be more fully understood and appreciated, I will now take up a detailed description, in which I will set forth the several features therof as fully and as completely as I may.

In the drawings letter A denotes the bottom or floor of a wagon-bed, from which ex-

tend upward the sides B and C in the usual manner. The inner corners of the sides B and C are truncated or beveled, as at α .

Inclosing the rear ends of the sides B and C are the respective caps or hooder-irons 1 and 2, which snugly fit said sides and conform with the bevels α , and they extend from the top to the bottom thereof, and they are secured by the rivets y as shown.

Numerals 3 and 4 denote the hanger-hooks, the same being attached as by rivets z to near the upper ends of the outer members of their respective hooder-irons, and they are notched into the respective sides B and C as shown in Fig. 4, and they project rearward from the ends of said sides as shown in Fig. 3.

Numerals 5 and 6 denote the shackle-irons, the same being attached, as by rivets e , to near the lower ends of the outer members of their respective hooder-irons, and they are notched into the respective sides B and C in the same manner as are the hooks 3 and 4, and they project rearward from said sides as shown in Fig. 3. Each of said shackles has an eye therein, as the eye f in Fig. 3.

Numeral 7 denotes the end-gate proper, the same having an acute angular tongue p extending laterally from the rear edge of each end thereof, to conform with the respective bevels α shown in Fig. 2. Secured on the rear, outer, face of the gate 7 and extending vertically across each end thereof, are the outer metal plates 8 and 9, which merge into their respective angle-irons 10 and 11. Covering the ends of the gate 7, fitting said angular portions p , and connected with the angle irons 10 and 11, is an edge plate, as the edge-plate 12 shown in Fig. 2, the same being integral with their respective inner plates, as the inner plate 13 shown in Fig. 2. By the arrangement of the above it is seen that I form a channel between the respective angle irons and its plate 12 in which channel will fit the rear ends of the said sides B and C, all as is clearly shown in Fig. 2.

Formed through the upper portion of the angle-irons are the respective slots 14 and 15 which are to receive the respective hooks 3 and 4 therein.

Similar to the above are the slots 16 and 17 formed through the lower portions of the

angle-irons to receive therein the respective shackle-irons 5 and 6.

In this instance I provide my gate with two eccentric latches which are identical with each other, each comprising a base-plate 18 to which is secured the hinge-plate 19, the latter being provided with ears through which is disposed the vertical bolt 20. Numeral 21 denotes the handle which is integral with the shank 22, the latter being integral with the head 23, which is rotatable between the said ears of the plate 19, where it is pivoted on the said bolt, substantially as shown.

Numeral 24 denotes a fork which is pivoted to the central portion of the shank 22, by means of the bolt 25. Extending from the fork 24 is a plunger 26. A flange 27 extends out from the plunger 26, and it is located a short distance from said fork. Said flange 27 forms a stop against which one end of the spring 29 is at all times engaged.

Secured on the outer plates, 8 and 9, are the guide bearings 28 which has an eye therethrough in which is slidably mounted the plunger 26, but which is adapted to be withdrawn therefrom.

Surrounding the plunger 26 and extending between the guide 28 and the stop 27, is the helical spring 29, which is adapted to keep the plunger 26 in either its securing or non-securing position, that is to say: inserted or withdrawn.

Extending from the plunger 26 is a finger 30 which, when the handles are thrown apart, enters a slot in the base portion of the handles, there being a hole formed through the projecting portion in which may be inserted a pin 31, or a padlock may be employed in place of the pin, but in ordinary practice neither the pin or a padlock will be used.

It will now be seen that if the handles 21 be thrown apart, as in Fig. 1, that the outer ends of the plungers 26 will be driven unto the eyes of the respective shackles 5 and 6, thereby locking the end gate in such position that it can not be inadvertently removed, and at the same time, by reason of the hooks 3 and 4 being in the eyes 14 and 15, the sides B and C will be prevented from spreading apart, and the end-gate can not become loosened.

Now when one desires to open the rear end of the vehicle-bed he has only to grasp the two handles 21 and simultaneously draw them toward each other, which after the movement has reached a certain point, by reason of eccentric mounting, will be retained in that position by the spring 29.

It is evident that when the handles are moved toward each other that the plungers 26 will be drawn from engagement with the shackles 5 and 6, therefore the operator may, while still holding the handles, pull outward thereon and thus swing the end-gate outward and upward, thereby permitting material to pass from the bed under gate. Or if it be desired, the operator still holding the handles 21, he may swing the end-gate further upward and at the same time he may lift upward thereon, thereby removing it from engagement with the hooks 3 and 4.

To replace the end-gate one has only to reverse the operations just mentioned, thereby bringing the end-gate back to operative position in an infinitesimally short space of time.

I desire that it be understood that various changes may be made in the several details of construction from that herein shown without departing from the spirit of the invention and without sacrificing any of the advantages thereof.

Having now fully shown and described my invention, what I claim and desire to secure by Letters Patent of the United States, is—

In combination with a vehicle bed adapted to receive an end gate to close the end thereof, flat-hooks extending out and back from the end of the upper portion of the bed, shackles extending out and back from the lower portion of the end of the bed, an end gate having channels at each end to receive the ends of the sides of the bed, there being slots in the bottoms of said channels through which said hooks and shackles project rearward beyond the end gate with the end gate suspended upon said hooks, plungers adapted to enter eyes in said shackles to lock the end gate in operative position, handles for manually operating said plungers, and spring means for positively holding the plungers resiliently in or out of operative position.

JOSEPH M. GRAY.
